UNITED STATES PATENT OFFICE

102,240

DESIGN FOR AN EYEGLASS FRAME

Isaac M. Schwab, Savannah, Ga.

Application August 25, 1936, Serial No. 64,570

Term of patent 7 years

To all whom it may concern:

Be it known that I, Isaac M. Schwab, a citizen of the United States, residing at Savannah, in the county of Chatham and State of Georgia, have invented a new, original, and ornamental Design for an Eye Glass Frame, of which the following is a specification, reference being had to the accompanying drawing, forming part thereof.

In the drawing:

Fig. 1 is a front elevational view of an eye glass frame, showing my new design, the dominant features of which are the nose guards shown in full lines.

Fig. 2 is a top plan view of one of the nose guards; and

Fig. 3 is a side elevational view of the same.

I claim:

The ornamental design for an eye glass frame, as shown and described.

ISAAC M. SCHWAB.
